CLAIM

The ornamental design for a mobile communication device, as shown and described.

DESCRIPTION

FIG. 1 is a perspective view of a mobile communication device showing the claimed design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines immediately adjacent the claimed areas, which encompass non-shaded regions, represent the bounds of the claimed design, while all other broken lines are directed to environment and are for illustrative purposes only; the broken lines form no part of the claimed design. The entire surface of the front cover's interior forms no part of the claimed design.
